ABRAM N. PASMAN, OF WATERBURY, CONNECTICUT, ASSIGNOR TO SCOVILL MANUFACTURING COMPANY, OF WATERBURY, CONNECTICUT, A CORPORATION OF CONNECTICUT

WASTE-PIPE FITTING

Application filed June 6, 1929 Serial No. 368,965.

My present invention relates to a waste pipe fitting and more particularly to that type of waste pipe fitting especially adapted for use in connection with sinks and similar fixtures 5 and in which, together with a coupling for connecting the sink to a waste pipe or drain, there is provided a stopper movable within the coupling to and from seated and unseated positions with a strainer member associated 10 with the stopper so as to be movable therewith within the coupling, the stopper and strainer member preferably being entirely removable as a unit from the coupling in order to empty the strainer member and to adequately clean the same. I am aware that heretofore various types of waste pipe fittings of 15 this character have been proposed whereby in the use thereof the stopper and strainer member may be moved to a position in which 20 the stopper is seated in order, for example, to retain water in the sink, causing the sink to be usable as a dish pan or basin, and to move the stopper and strainer so that the stopper is unseated and the strainer and stopper are 25 supported in a position in which the stopper is unseated, permitting the water to flow from the sink, or other fixture with which the fitting is associated, and at the same time retaining in the strainer member any particles of 30 foreign matter which do not pass through the same.

In this type of device, however, so far as the same has come to my attention, the parts have been so constructed that it is necessary to 35 set the stopper and strainer in a predetermined position, or one of a number of predetermined positions, in order to effect the movement thereof to seat and unseat the stopper and, moreover, to turn the strainer member and stopper a predetermined portion of a revolution when raised to the position in which the stopper is unseated, in order to support the same in this position. These structures, therefore, require more or less precision 40 in placing the parts thereof in position to be operable. The structure made in accordance with my invention is an improvement on this type of waste pipe fitting. In carrying out the invention the same includes 45 a coupling associated with which there is a

stopper and preferably a strainer member or dish, together with means whereby the stopper, or the stopper and strainer dish, are movable when in any revoluble position within the coupling to and from positions in which 55 the stopper is seated and unseated and when unseated the stopper, or the stopper and strainer dish, are yieldingly supported. Moreover, the strainer dish is revolubly connected to the stopper and in the positioning 60 of the parts in the coupling means are provided for centering the same and also for guiding the movements thereof to and from the seated and unseated positions. By this construction, as hereinafter more particularly described, the stopper member, together with the strainer dish, may be placed and operated in any revoluble position in the coupling and are revoluble relatively to each other, and this condition maintains whether 65 these parts are in the position in which the stopper is seated or unseated, thereby facilitating the manipulation of the parts of the apparatus when in use and also materially increasing the useful life thereof. 70

In the drawing Figure 1 is a plan of a sink drain fitting made in accordance with my invention,

Fig. 2 is a central longitudinal section taken on line 2—2, Fig. 1 showing the stopper in an 80 unseated position,

Figure 3 is a view similar to Fig. 2 showing the stopper in its seated position,

Fig. 4 is an elevation of the body of the stopper, viewing the same from a position at 85 right angles to that shown in Figs. 2 and 3, and

Fig. 5 is a plan of the stopper member.

Referring to the drawings the waste pipe fitting made in accordance with this invention 90 is constructed to include a coupling 10 which is preferably cup shaped and at its upper or outer end is provided with a flaring flange 11 adapted to be received in a recess provided therefor in the wall of a sink, basin, or similar fixture, indicated at 12. The coupling is secured in position in the wall of the sink by means of a clamp nut 13 and an intervening gasket 14. The inner or reduced lower end 15 of the coupling is constructed to be connected 95 100

to a waste or drain pipe 16 by a clamp nut 17 and an intervening gasket 18, or otherwise.

In the reduced end 15 of the coupling there is a transverse bar 19 preferably made integral therewith and in which there is mounted a post 20. This post 20 functions as a centering post, a guide post and a support post, as will hereinafter appear. The upper end of this post 20 is provided with a head which is slightly flaring, as indicated at 21.

Interiorly the reduced portion of the coupling is provided with a stopper seat 22 below which and between the same and the cross bar 19 this end of the coupling is formed interiorly to include a shoulder 23 adapted to receive, seat and support an inner strainer plate 24. Interiorly in the outer portion of the larger end of the coupling there is also a shoulder indicated at 25.

Associated with the coupling there is a stopper or plug member 26. The lower peripheral portion of the stopper 26 is provided with a beveled face 27 adapted to fit against the stopper seat 22. The body of the stopper is made to include a central longitudinally disposed opening 28 which extends through the stopper body and into the stem 29 thereof. The diameter of the opening 28 is substantially the same as that of the enlarged end of the head 21 of the post 20. The extremity of the stem is of reduced diameter, as indicated at 30 and between the end of the stem and the main portion thereof there are shoulders indicated at 31 and 32. In oppositely disposed positions in the upper portion of the body of the stopper there are radially disposed ribs 33 and 34. In the rib 33 there is a bore 35 having at the inner end thereof a bearing for a ball 36. Lying within the bore there is a spring 37 which extends between the ball 36 and a plug 38 adapted to be turned down in the tapped outer end of the bore to adjust the tension of the spring and consequently to correspondingly vary the pressure with which the ball 36 is normally maintained against its seat. When seated, as indicated in Figs. 2 and 3, a portion of the ball protrudes into the opening 28. In a similar manner the rib 34 is provided with a bore 39 at the inner end of which there is a seat for a ball 40. Lying within the bore there is a spring 41 extending between the ball and the inner end of a plug 42. The plug 42 may be adjusted to position in the tapped outer end of the bore 39 in order to vary the tension on the spring and consequently to correspondingly vary the pressure with which the ball 40 is normally maintained against its seat. This ball 40 extends into the opening 28 in the same manner and to the same extent as the ball 36.

Associated with the stopper there is a strainer member 43. This strainer member is preferably dish or cup shaped and at its outer

end is flared, as indicated at 44. The flared end of the strainer dish forms a lip which is of substantially the same outer diameter as the inner diameter of the outer portion of the coupling. The strainer dish is provided with a plurality of apertures of sufficient number and size to normally permit the liquid to flow through the strainer dish but to retain foreign matter which may be in the liquid and of sufficient size not to pass through the apertures therein. In the bottom wall of the strainer dish there is an opening of substantially the same diameter as that of the shoulder 31, whereby the shoulder 31 is adapted to pass through this opening and the bottom wall of the strainer dish to normally rest upon the shoulder 32. It is to be noted that the thickness of the bottom wall of the strainer dish is appreciably smaller than the distance between the shoulders 31 and 32.

The apparatus furthermore includes a lift stem 45. One end of this lift stem is preferably enlarged, as indicated at 46 to form a head therefor, while in the opposite end of the lift stem there is a tapped opening for the reception of the reduced screw threaded end or extremity 30 of the stem 29 of the stopper member. The lift stem is adapted, therefore, to be screwed down on this reduced end of the stopper member and when in place to bear against the shoulder 31. In order to lock the lift stem in position I may employ a screw 47. This screw passes through the bore provided therefor in the reduced end 30 of the stem of the stopper and is adapted to be turned down in a tapped portion of the lift stem 45, with the head of the screw 47 lying against the face or wall defining the inner end of the opening 28 in the stopper.

In the device as hereinbefore described the strainer dish is revolvably connected to the stopper and maintained in position between the same and the lift stem. As clearly illustrated there is also a slight longitudinal movement made possible between the strainer dish and the stopper because, as hereinbefore described, the thickness of the bottom wall of the strainer dish is slightly less than the distance between the shoulder 32 on the stem of the stopper and the inner or lower end of the lift stem 45. The stopper and the strainer dish are completely removable from the coupling for the purpose of emptying the strainer dish and cleaning the same, or for other purposes, and when removed the plate 24 functions as a strainer in the use of a sink or basin, or other fixture in which the fitting is employed. The stopper and the strainer dish associated therewith may be placed in the coupling and in doing so the head of the post 21 enters the opening 28 in the stopper member and functions to center the same. Normally the head of the post 20 enters this opening until it comes into contact with the

balls 36 and 40, which function as a support member to normally maintain the stopper and the strainer dish associated therewith in a raised position in which, as illustrated in Fig. 2, the stopper is appreciably removed from its seat and the flared rim or lip portion 44 of the strainer dish lies within the upper portion of the coupling, thereby permitting water to flow into and through the strainer dish and around the stopper to the waste pipe 16, the strainer disk retaining therein particles of foreign matter which may be contained in the water and the strainer plate 24 preventing any particles which may pass through the strainer dish from passing to the waste pipe. The stopper may be seated by merely forcing the same downwardly or inwardly, causing the balls 36 and 40 to recede from their normal positions against the action of the springs 37 and 41 to permit the head 21 of the post 20 to pass further into the opening 28. At the same time the head end of the post 20 functions as a guide for directing the stopper to its seat. The seated position of the stopper and the corresponding position of the strainer dish are indicated in Fig. 3. In this position the opening to the waste pipe is closed and the sink or other fixture may be filled with water to a desired extent and employed as a dish pan, or basin, or otherwise.

It will now be apparent that in the construction of the waste pipe fitting as described the stopper member and the strainer dish associated therewith may be placed in the coupling in any position and in any position these parts may be supported with the stopper member unseated. Likewise in any position the stopper and the strainer dish associated therewith may be moved to the position in which the stopper is seated. Furthermore, the stopper as well as the strainer dish are revoluble relatively one to the other in either the seated position of the stopper, or the unseated position thereof, or in any intermediate position. By this construction, therefore, it is unnecessary to place the stopper and its strainer dish in any particular position in the coupling, or to set these parts in any particular position to move the same to a position in which the stopper is seated or unseated which makes it possible to seat the stopper in any revoluble position thereof relatively to the coupling, thereby increasing the useful life of the stopper. It is also possible, if necessary, to turn the stopper when the same is seated to cause it to seat more tightly, for example, by crushing or grinding particles of matter which may adhere to the tapered face of the stopper, or to its seat, or for other purposes. Moreover, when the stopper is seated it is possible, if necessary, to turn the strainer dish to any desired position relatively to the stopper and within the coupling. The peripheral portion 44 of the

strainer dish fits closely within the outer portion of the coupling and the purpose of permitting a slight longitudinal movement of the strainer dish relatively to the stopper is to assist the stopper in properly seating in the event of the peripheral portion of the strainer dish being bent, or otherwise put out of shape in the use thereof. It will be furthermore understood that the construction of the apparatus as herein illustrated and described is illustrative of what I now consider the preferred form thereof, but that this may be varied to employ equivalent constructions without departing from the nature and spirit of the invention.

I claim as my invention:

1. In a waste pipe fitting, a coupling, a stopper member adapted to seat within the coupling, a strainer dish mounted to turn freely on the stopper member, and means for 85 yieldingly supporting the stopper member and strainer dish with the stopper member in an unseated position, the said stopper member and strainer dish being revoluble independently of one another to any position in 90 the coupling and entirely removable as a unit from the coupling.

2. In a waste pipe fitting, a coupling, a stopper movable within the coupling to and from seated and unseated positions, a 95 strainer dish, said stopper and strainer dish being connected to turn freely relatively to one another and to the coupling when in any position for use, and means for guiding the said stopper and strainer dish to and from the seated and unseated positions of the stopper and yieldingly supporting the stopper and strainer dish when the stopper is in its unseated position, the stopper and strainer dish being removable as a unit from 100 the said coupling.

3. In a waste pipe fitting, a coupling, a stopper movable within the coupling to and from seated and unseated positions, a strainer dish, said stopper and strainer dish being mounted to turn freely relatively to one another and to the coupling when in any position for use, and means for centering the said stopper and strainer dish within the coupling, for guiding the said stopper and the strainer dish to and from the seated and unseated positions of the stopper, and for yieldingly supporting the stopper and strainer dish when the stopper is in its unseated position.

4. In a waste pipe fitting, a coupling, a stopper, a strainer dish, the said stopper and strainer dish being movable within the coupling to and from positions in which the stopper is seated and unseated, and being connected to turn freely relatively to one another and to the coupling when in any position for use, and means for yieldingly supporting the stopper and strainer dish when the stopper is in its unseated position.

5. In a waste pipe fitting, a coupling, a stopper, a strainer dish, a lift stem connected to the stopper and adapted to continuously maintain the strainer dish in association therewith, and means for locking the lift stem in position on the stopper, the said stopper, strainer dish and lift stem being entirely removable as a unit from the said coupling. 70
10. 6. In a waste pipe fitting, a coupling, a stopper, a strainer dish revoluble on the stopper, a lift stem connected to the stopper with a portion of the strainer dish intermediate between the same and the stopper, and means for locking the lift stem to the said stopper, the said stopper, strainer dish and lift stem being movable within the stopper to and from positions in which the stopper is seated and unseated and also being entirely removable as a unit from the said coupling. 75
15. 7. In a waste pipe fitting, a coupling, a stopper, a strainer dish revoluble on the stopper, a lift stem connected to the stopper with a portion of the strainer dish intermediate between the same and the stopper, and a lock screw passing through a portion of the stopper and into the said lift stem for locking the lift stem to the said stopper, the said stopper, strainer dish and lift stem being movable within the stopper to positions in which the stopper is seated and unseated and also being entirely removable as a unit from the said coupling. 80
20. 8. In a waste pipe fitting, a cup shaped coupling having a stopper seat in the inner portion thereof, a post mounted in a centrally disposed position in the inner end of the coupling, a stopper, and means carried by the stopper for yieldingly supporting the same from the outer end of the post when in an unseated position. 85
25. 9. In a waste pipe fitting, a cup shaped coupling having a stopper seat interiorly in the inner portion thereof, a post mounted to extend longitudinally in a centrally disposed position in the inner portion of the coupling, a stopper adapted to bear against the said stopper seat when in one position, and yieldingly mounted members carried by the said stopper and adapted to engage the end of the said post to yieldingly maintain the stopper in an unseated position within the said coupling. 90
30. 10. In a waste pipe fitting, a cup shaped coupling having a stopper seat interiorly in the inner portion thereof, a post mounted to extend longitudinally in a centrally disposed position in the inner portion of the coupling, a stopper adapted to bear against the said stopper seat when in one position, the said stopper having a centrally disposed opening adapted to receive the said post and also having radially disposed bores, a ball at the inner end of each of the said bores in the stopper, and adjustable means for yieldingly maintaining the said balls in a position in which they protrude into the opening in the stopper to contact with the end of the post to yieldingly maintain the stopper in an unseated position within the said coupling. 95
35. 11. In a waste pipe fitting, a cup shaped coupling having a stopper seat interiorly in the inner portion thereof, a post mounted to extend longitudinally in a centrally disposed position in the inner portion of the coupling, a stopper adapted to bear against the said stopper seat when in one position, the said stopper having a centrally disposed opening adapted to receive the said post and also having radially disposed bores, a ball at the inner end of each of the said bores in the stopper, and a spring and plug in each of the said bores in the stopper for yieldingly and adjustably maintaining the said balls in normal positions in which they project into the said opening in the stopper whereby the balls are adapted to engage the end of the said post to yieldingly maintain the stopper in an unseated position within the coupling, the said post operating in the opening in the stopper thereby functioning as a means for centering the stopper and guiding the same in the movements thereof to and from its seated and unseated positions. 100
40. 12. In a waste pipe fitting, a cup shaped coupling having a stopper seat in the inner portion thereof, a post mounted in a centrally disposed position in the inner end of the coupling, a stopper, a strainer dish revolubly connected to the stopper and having a slight longitudinal movement relatively thereto, and means carried by the stopper for yieldingly supporting the same and the strainer dish on the outer end of the post when the stopper is in an unseated position. 105
45. 13. In a waste pipe fitting, a cup shaped coupling having a stopper seat interiorly at the inner end thereof, a post mounted to extend longitudinally in a centrally disposed position in the inner portion of the coupling, a stopper adapted to bear against the stopper seat when in one position, a strainer dish revolubly connected to the stopper, and yieldingly mounted members carried by the stopper and adapted to engage the end of the said post to yieldingly maintain the stopper and the strainer dish in a position in which the stopper is unseated. 110
50. 14. In a waste pipe fitting, a cup shaped coupling having a stopper seat interiorly adjacent the inner end thereof, a post mounted to extend longitudinally in a centrally disposed position in the inner portion of the coupling, a stopper adapted to bear against the stopper seat when in one position, the said stopper having a centrally disposed opening adapted to receive the said post and also having radially disposed bores, a ball at the inner end of each of the said bores in the stopper, and a strainer dish revolubly connected to the 115

stopper, a ball at the inner end of each of the said bores in the stopper, and adjustable means for yieldingly maintaining the said balls in a position in which they protrude into the opening in the stopper to contact with the upper end of the post to yieldingly maintain the said stopper and the strainer dish in a position in which the stopper is unseated.

15. In a waste pipe fitting, a cup shaped coupling having a stopper seat interiorly in the inner portion thereof, a post mounted to extend longitudinally in a centrally disposed position in the inner portion of the coupling, a stopper adapted to bear against the said stopper seat when in one position, the stopper having a centrally disposed opening adapted to receive the said post and also having radially disposed bores, a strainer dish revolubly connected to the said stopper, a ball at the inner end of each of the said bores in the stopper, a spring and plug in each of the said bores in the stopper for yieldingly and adjustably maintaining the said balls in normal positions in which they project into the said opening in the stopper whereby the balls are adapted to engage the end of the said post to yieldingly maintain the stopper and the strainer dish in a position in which the stopper is unseated, the said post operating in an opening in the stopper, thereby functioning as a means for centering the stopper and guiding the same in the movements thereof to and from its seated and unseated positions.

16. In a waste pipe fitting, a coupling, a stopper movable within the coupling to and from seated and unseated positions, and a strainer dish revolubly mounted on and movable with the stopper within the coupling, whereby said stopper and strainer dish are adapted to turn freely relatively to one another and to the coupling when in any position within the coupling, and are removable as a unit from the coupling.

17. In a waste pipe fitting, a coupling, a stopper movable within the coupling to and from seated and unseated positions, a strainer dish mounted to turn on the said stopper, the said stopper and strainer dish being adapted thereby to turn freely relatively one to another and to the coupling when in any position for use, and means for yieldingly supporting the stopper and strainer dish when the stopper is in an unseated position, the said stopper and strainer dish being removable as a unit from the said coupling.

Signed by me this 27th day of May, 1929.
ABRAM N. PASMAN.
